United States Patent Office.

ANTONIO F. SMITH, OF ELLSWORTH, MAINE.

Letters Patent No. 73,762, dated January 28, 1868.

IMPROVEMENT IN STOVE-DRUMS.

The Schedule referred to in these Letters Patent and making part of the same.

TO ALL PERSONS TO WHOM THESE PRESENTS SHALL COME:

Be it known that I, ANTONIO F. SMITH, of Ellsworth, in the county of Hancock, and State of Maine, have invented a new and useful Ventilator and Spark-Arrester, to be applied to the smoke-discharge pipe of a stove, and I do hereby declare the same to be fully described in the following specification, and represented in the accompanying drawings, of which—

Figures 1 and 2 are vertical sections, and

Figure 3 a horizontal section of it.

In such drawings, A denotes a square box, provided with a frusto-conical bottom, whose opening, a, is provided with a cylindrical neck, b, to enter and fit to the smoke-discharge pipe of a stove. Over this bottom, and projecting therefrom, is a hollow, conic, pyramidal frustum, B, which is open at top, there being a space between such top and the top plate c of the box A. A concavo-convex disk, or spark-deflector, D, is arranged within the frustum B, or with respect to it and the conical bottom of the box A, in manner substantially as represented in figs. 1 and 2, it being supported by arms, d, extended from it to the box A. There is an eduction-passage or neck, E, leading out of one side of the box A, and against the other or opposite side is a long chamber, F, extending across the box, and being provided with openings, e e, leading into it, such openings having a slide valve or register, f, applied to them, the handle or knob of the valve being shown at g. There extend from and open out of the chamber F, two pipes, G G, which go through the box A, and lead into the discharge-opening E thereof.

The apparatus so made is intended to be applied to the smoke-discharge flue of a stove in such manner as to cause smoke, after escaping from the stove, to pass through its discharge-pipe, and into and through the apparatus, in manner as exhibited by the arrows in figs. 1 and 2. By the action of the deflector D many of the sparks will be arrested, while the smoke, with the rest, will be deflected around the edge of the deflector, and caused to pass into the cone pyramidal frustum B. This frustum will also operate to arrest the sparks, many of which, in passing out of the discharging-mouth of the frustum, will fall into the box A, or the space thereof surrounding the frustum.

The pipes G G, when heated by the smoke, will cause currents of air to escape from the apartment in which the stove may be situated, and thus the room will be ventilated and freed of any foul air, gas, or smoke. The soot and carbonaceous matters in the smoke will be intercepted, and what is not thrown back into the pipe by the deflector will pass into that part of the box A above the cone pyramidal frustum, where it will be deposited, and most of it will be burned. The top of the box A, I apply to the rest of the box by hinges, l, or by other means, by which such top may be removed from the box, as occasion may require, in order to enable access to be had to the box for removal of the ashes which may accumulate therein. The transverse chamber, with its register or air-valve, enables air to be supplied to both the air-pipes, and in quantities as may be desirable from time to time.

My present invention is a great improvement with reference to that patented by me in Letters Patent, No. 70,087, dated October 22, 1867, as it enables me to avoid the employment of the foraminous or perforated partitions incident to such, the holes of which were soon liable to become choked by soot and cinders.

What I claim as my present invention, is—

The arrangement as well as the combination of the hollow frustum B with the deflector D, and the box A provided with induction and eduction-passages or conduits b E, arranged in it as specified.

I also claim the arrangement as well as the combination of the auxiliary air-chamber F, and its air-register or valve, and opening or openings with the box A, the frustum B, or the said frustum and its deflector D, the whole being substantially as specified.

ANTONIO F. SMITH.
